(57) **CLAIM**

The ornamental design for a football night light ultrasonic pest repeller, as shown and described.

DESCRIPTION

FIG. 1 is a perspective view of the football night light ultrasonic pest repeller.

FIG. 2 is a front view of the football night light ultrasonic pest repeller.

FIG. 3 is a rear view of the football night light ultrasonic pest repeller.

FIG. 4 is a right side elevational view of the football night light ultrasonic pest repeller.

FIG. 5 is a left side elevational view of the football night light ultrasonic pest repeller.

FIG. 6 is a top view of the football night light ultrasonic pest repeller; and,

FIG. 7 is a bottom view of the football night light ultrasonic pest repeller.

The portions of the night light shown in broken lines form no part of the claimed design.
